poration of Massachusetts

Application June 25, 1940, Serial No. 342,323

30 Claims. (Cl. 66—9)

This case concerns an invention in the knitting art, and more especially, a method and mechanism employed in knitting fabrics having incorporated therein elastic yarn. The elastic yarn is preferably to be incorporated by inlaying and according to the method practiced and mechanism employed certain advantages are forthcoming tending toward a better fabric both with respect to its elastic characteristics and other characteristics including plating of yarns as for ornamental purposes, the method and mechanism employed being of such a nature as to handle the elastic without interference at the knitting point in regard to knitting or other manipulation of the non-elastic yarns. This case is a continuation as to all common subject matter of applicant's co-pending application Serial #332,161, filed April 29, 1940, Pat. No. 2,247,343.

In the figures of drawings:

Figs. 1, 2, 3 and 4 show successive steps in needle and sinker movement before and at the elastic yarn feeding point;

Fig. 5 is an isometric view showing feeding of the elastic yarn and the manner in which needles and sinkers are controlled in the initial stages of inlaying that yarn;

Fig. 6 is a section showing a few needles and sinkers after elastic has been interlaced to the front and back of needles, and the manner in which the elastic is controlled by sinkers;

Fig. 7 is a plan of the sinker cam cap and certain of the sinker cams which affect the movement of sinkers at the elastic yarn feeding point;

Fig. 8 is a diagrammatic view showing needle cams and the path of needle and jack butts at the main feeding point and at the elastic yarn feeding point;

Fig. 9 is a section showing part of a needle, a jack beneath the needle and a needle raise cam;

Fig. 10 is a plan view showing modified sinker cams at the main mouthpiece or feeding station illustrating the pathway of sinker butts at that point, also the manner in which needles are affected by the elastic yarn before arriving at the knitting point and at that point;

Figs. 11, 12 and 13 are detail views showing a sinker and the method in which elastic yarn is drawn over some raised portion of the sinker and thereafter dropped to a lower level prior to arriving at the main yarn feeding station;

Fig. 14 is a plan showing the elastic yarn feeding means, some of the control therefor, and control for the elastic yarn binder;

Fig. 15 is a view showing certain parts in sec-
tion and illustrating the relative position and

construction of the elastic yarn binder and cer-
tain operating parts functioning therewith;

Fig. 16 is a detail of cam mechanisms employed
to actuate the elastic yarn feeding means;

Fig. 17 is an elevation at one side of the ma-
chine which further illustrates the elastic yarn
feeding means and operating mechanism asso-
ciated therewith; and

Fig. 18 is a diagrammatic view showing a modi-
fication involving an elastic yarn feed and two
non-elastic yarn feeding stations, needle and jack
cams for the same, and needle and jack butt
pathways incidental to elastic yarn knitting.

Inlaying elastic yarn in plain knitted fabric
15 has heretofore involved certain difficulties with
regard to control of tension on the yarn and ulti-
mate tension or stretch of a resulting fabric such
as a self-supporting stocking top. Prior methods
and means employed have also involved inter-
lacing of the elastic to the front and in back of
20 needles under such tension as to spring the needle
hooks out of alignment. This condition has pre-
vailed or existed at the main feeding station or
mouthpiece and, when it has been desired to feed
25 yarns in plating relation therat, the success of
the plating has been seriously jeopardized by this
misalignment of needles. The method and mech-
anism herein described and which are continua-
30 tions in certain respects of subject matter of
application Serial #332,161 serve very effectively
to alleviate the difficulties above mentioned.

Elastic yarn subsequently to be cleared below
needle latches and to be cast off into a plain
knitted fabric as an inlaid yarn is fed at a point
35 preceding the main mouthpiece or feeding sta-
tion, or at least one of such stations. Accord-
ing to the present method that yarn is fed to the
hooks of needles and is later to be cleared or
passed below needle latches. Rather than feed-
40 ing over the lower surface forwardly of sinker
throats, feeding is at a comparatively elevated
position, preferably over sinker nibs. This elastic
yarn feeding station preceding a main feeding
45 station has sinkers so controlled that the elastic
will be drawn over alternate sinker nibs or other
raised surfaces with respect to a surface to which
said elastic yarn may later be moved, best results
being obtained when drawing over nibs of alter-
nate sinkers. This is on the assumption that the
50 said elastic yarn is to be inlaid according to a
1 x 1 arrangement, that is, by alternate needles.
If other spacing is desired, of course, a different
selection and control of sinkers would be de-
sirable.

Referring to Figs. 1 through 4, sinkers general-

ly designated by numeral 1 are arranged as usual to be controlled by sinker cams effective on butts at the outer ends of the sinker stems. Two types of sinkers are employed, one having standard nibs 2 and another having flat nibs 3. The sinkers having standard nibs are also equipped with long butts 4 while those having flat topped nibs are provided with short butts 5. Latch needles 6 of conventional construction function in the usual manner. In Fig. 1 the sinkers are shown as they might be controlled at the main mouth-piece whereat non-elastic yarn or yarns may be fed and needles would draw stitches at that point over a surface indicated at 7 and more or less horizontally disposed at the lower level of sinker throats 8. In Fig. 2 sinkers have all been controlled to cast off as is the usual practice and needles are thereafter raised, Fig. 3, so as to bring needle hooks to an elevated position for taking elastic yarn, the needles not, however, being raised sufficiently to clear their latches of the non-elastic yarn. An elastic yarn guide 9, Fig. 3, feeds an elastic yarn 10 to the hooks of needles, all sinkers being pushed inwardly at that particular time. The sinkers are in effect in the same position they occupied after casting loops from the needles. In Fig. 4 a further step is illustrated wherein the standard type sinkers having long butts are withdrawn while the flat topped sinkers are maintained in advanced position so that the elastic yarn will be drawn over the tops of the sinker nibs. By this a much greater amount of elastic yarn is initially measured off due to kinking of the yarn or, in effect, what might be termed elongated stitches of elastic are drawn. It is true that these are not stitches in the sense that they ultimately become knitted loops since the elastic yarn is later cleared below needle latches and passes from the main knitting point as an inlaid yarn. While a great deal of elastic yarn is drawn by this method, the elastic yarn is not actually drawn through a previously drawn loop nor is any previously drawn loop cast from the needle at this point.

At Fig. 5 the elastic yarn feeding finger, or the lower end thereof, is shown in the position it occupies during feeding its yarn and several sinkers and needles are illustrated in about the relative positions they occupy just after passing that feeding means. It will be noted that standard sinkers having nibs 2 are drawn rearwardly while the flat topped sinkers remain in forward position. Alternate needles are selected to rise for taking the elastic yarn while intermediate needles remain at a much lower elevation. The elastic yarn may be drawn downwardly to any extent desired so long as non-elastic yarn loops in needle hooks are not strained. Obviously the height of the special or flat topped sinker nibs, or other surface over which the elastic is drawn, determines the ultimate amount of elastic that can be measured by this system.

After the elastic has been drawn needles are raised and this includes needles which were previously in a lower position, that is, those intermediate needles not selected. Plain sinkers having nibs 2 are pushed inwardly as and for the purpose described in co-pending application Serial #254,247, filed February 2, 1939, the said sinkers holding the elastic yarn in their throats and in such position that when intermediate needles move up the elastic will float behind them.

In Fig. 6 five needles and five sinkers are shown, the elastic being indicated as held beneath nibs 2 of so-called plain sinkers and

over the nibs 3 of special sinkers. Previously formed fabric is indicated at 11 as resting in sinker throats. The nibs 2 of the plain sinkers also serve to hold the elastic down on the needles. Of course all needles move upwardly after the elastic is drawn and remain in a position with the elastic hanging on the latches until they move up the front stitch cam at the main feed at which time latches are cleared.

10 Referring to Figs. 7 and 8, cams have been shown such as would be employed on a plain machine and for the purpose of controlling sinkers and needles at the main feed or mouthpiece as well as at the elastic yarn feeding station. A 15 sinker cam cap 12 carries side sinker cams 13 and 14 and a center sinker cam 15. Sinker butts are controlled by these cams so that the sinkers themselves pass in an appropriate sinker wave at this point in the machine. A cam 16 of triangular shape is so mounted and constructed as to engage long sinker butts 4 only and draw those sinkers outwardly. There is a corresponding triangular notch or indentation 17 opposite the cam 16 in the end of the side sinker cam 14. The cam 16 and the notch 17 function to impart movement to so-called plain sinkers as described above with respect to Figs. 4 and 5. Short butts 5 pass beneath cam 16 and thus the special sinkers having nibs 3 are unaffected 20 at this position. A few sinkers have been illustrated in Fig. 7, it being noted that every other sinker is drawn outwardly while intermediate sinkers remain projected fully inward. Cam 18 of usual construction holds sinkers inwardly until 25 they are again controlled by the front side sinker cam 13 and center sinker cam 15.

30 Referring to Fig. 8 a cam plate 19 has fixed thereon a needle raise cam 20 while the main cam block carries stitch cams 21 and 22, center 35 raise cam 23 and a guard cam 24. These are of conventional construction and will not be described in further detail. The raise cam 20 is cut away to accommodate a stitch wave induced by cam 25. As shown in Fig. 9, each of the needles 40 6 has a butt 26, there being the usual division of long and short butts as in Banner hosiery machines. A short jack 27 has a butt 28 which rides along just above cam plate 19 and is guided within a space of triangular cross section formed 45 between the beveled lower edge of raise cam 20 and the top of plate 19. Cam 29 movable selectively to and from butt engaging position is adapted to contact these butts 28 and thereby raise jacks and incidentally needles so that the 50 hooks of needles take the elastic yarn and cam 25 may then function on butts 26 to draw down needles as illustrated in Figs. 3, 4 and 5. A jack 27 is provided beneath alternate needles or, of course, those needles which are selectively to be 55 elevated for taking the elastic yarn. Raise cam 20 is notched as indicated in Fig. 8 so that cam 29 may move to and from its active position and so that butts 28 may move up cam 29 and downwardly as the jacks themselves are pushed down 60 by needles. The surface 30 of raise cam 20 is of such a height that needle butts 26 move along at too low an elevation to engage elastic yarn 10. The cam is notched out beneath the point of elastic yarn drawing cam 25 and then an inclined surface 31 elevates all needle butts and needles back to the usual raise cam position.

65 Now referring to Figs. 14, 15, 16 and 17, certain parts of a typical hosiery machine have been shown sufficient to illustrate the essential elements entering into the performance of the

method herein described. A needle cylinder 32 is rotatable in the usual way carrying needles 6 and having the usual sinker assembly rotatable therewith of which the sinker cam cap 12 is a part. A carrier ring 33 is pivoted on post 34 and in an extension 35 has movably mounted a plurality of yarn feeding levers or guides 36. A binder for the yarns fed by levers 36 includes among other elements a supporting bracket 37, plate 38, main binder 39 and a cutter 40, Figs. 14 and 15. The main binder and cutter are operated by a lever 41, link 42 and extension 43, these elements being moved through a depending rod or link 44 which extends downwardly to certain connections at cams on a main cam drum.

The yarn feeding finger 9 extends upwardly and connects to one arm of a horizontally disposed lever 45. This lever 45 is pivoted on a shaft 46, Figs. 14 and 17, which passes through the upper end of post 34, but is fixed within the extension to the carrier ring 33 so that when the carrier ring is swung upwardly the shaft 46 turns with the carrier ring extension but turns within its bearing at the upper end of the post. A link or rod 47 connects at the outer end of the lever 45 and extends downwardly connecting to other elements so as to impart movements from certain cams on the main cam drum for withdrawing the elastic yarn feeding lever and allowing the same to drop to active position. The control for the main cam drum through the mechanism just described functions at the start or at the edge of a stocking top at which time the elastic yarn is first introduced and does not operate again until the said yarn is withdrawn at the end of knitting a top.

A secondary control is provided for this elastic yarn feeding means and this secondary control serves to move the elastic yarn feeding finger 9 from its lowermost position to a position in which its yarn will not be taken by needles, such movement being possible at every other course or at other spaced intervals according to the spacing of the elastic yarn desired. Of course, if the elastic is to be incorporated at each course in the fabric this secondary control is not used.

A shaft 48 is rotatable in bearing lugs 49 and 50, said shaft having at one end a vertically disposed finger 51 and at the other end a more or less horizontally disposed finger 52. The finger 51 contacts with a depending lever or arm 53 which is an integral or connected part with the lever 45. In an extension 54, a tappet 55 is adapted to slide vertically within a sleeve 56, Figs. 16 and 17. This tappet engages beneath the horizontal finger 52 at its upper end and at its lower end, is in alignment with certain cams 57 and 58, diametrically opposed on a drum 59 which rotates with 104-tooth gear 60 on shaft 61. The 104-tooth gear rotates one turn for every four revolutions of the needle cylinder so that when provided with two cams such as 57 and 58, the mechanism just described serves to raise the elastic yarn feeding means to inactive position once every two revolutions. The length of each of these cams is such as to hold the finger out of feeding position a complete revolution, while each space between cams allows the finger to remain in feeding position for the intervening revolution of the machine. The result is that the elastic will feed in every other course but will be floated across the needle cylinder at intervening courses. A suitable elastic yarn take-up is obviously to be used. A spring 62, Fig. 17, normally tends to maintain the elastic yarn feeding means in active

position. A stop 63 is so adjusted as to limit movement of depending arm 53 and thus movement of the feeding means 9 so that the end of the feeding means will, when in active position, just clear the tops of sinkers.

This feeding means is adapted to bring the elastic yarn very close to passing needle hooks, but as shown in Fig. 5, a projection 64 is so positioned as to force the yarn inwardly against the shanks of needles and beneath their hooks. This projection 64 is so shaped that the needle hooks passing above it are not affected thereby. Such close feeding makes certain that the elastic yarn when introduced is taken at the earliest possible needle.

The elastic yarn is to be taken within and cut by an independent binder which includes a vertically movable rod 65 slideable within a guiding sleeve 66. This rod 65 has at its lower end a notch 67 so constructed as to serve at one side to bind the elastic yarn against the lower edge of sleeve 66, and at the other side, is so constructed as to cut that yarn. A spring 68 normally tends to retain the binding and cutting elements in closed position. This binder and cutter are fully described and claimed in co-pending application Serial #330,857, filed April 22, 1940.

An arm 69, Figs. 14, 15 and 16 is fixed at one end of the shaft 46 and at its outer end serves to support a pivot 70 for a lever 71 which is curved inwardly and terminates in a flattened portion 72 bearing on the top of binder and cutter elements 65. A link 73 has a pin 74 at its upper end engageable above the lever 71. Said link 73 extends downwardly to connect either directly or indirectly to a lever 75 which is in turn controlled by certain cams on one of the main cam drums whereby the elastic yarn binder may be operated at desired intervals.

Since the arm 69 is fixed to the end of shaft 46 and shaft 46 in turn is adapted to move with carrier ring 33, whenever the ring is swung upwardly, the binder controlling means maintains its general position with respect to the elastic yarn binder and other elements. The link 73 does not move, but lever 71 moves out from beneath pin 74 so that the binder itself is unaffected. When the carrier ring is moved back to active or horizontal position the elements again assume their respective positions as shown in Fig. 15.

In Fig. 10 sinker cams, needles and sinkers are shown in positions they would occupy at about the main yarn feeding point. Cams illustrated herein are of a type employed in plating machines and include front and rear sinker cams 76 and 77 and center sinker cam 78. The sinkers are shown being controlled by these cams, a sinker wave being produced by center cam 78 which draws all sinkers outwardly and the point of cam 77 which projects them inwardly for casting off previously drawn loops. Elastic yarn is shown as having been taken in the hooks of alternate needles and floated behind intermediate needles while sinkers are all moved inwardly, the elastic being drawn over the nibs of alternate sinkers and being held within the throats of intermediate ones. This condition has prevailed after needles were drawn down by cam 25 and when their butts were riding upon the top surface of cam 20. It can be seen that under these circumstances the elastic is held under considerable tension and needles are bent forwardly and rearwardly according to whether the elastic passes in front of or behind the shanks. At about the outermost point of movement of sinkers as controlled by

cam 78, the elastic is dropped from the nibs or elevated surfaces over which it has been drawn and it can be seen that under those conditions the said elastic yarn loses its tension and needles assume proper alignment. The elastic yarn itself then becomes horizontally kinked as it passes to the front and back of alternate and intermediate needles, respectively. A non-elastic yarn is shown being taken within the hooks of needles at about the point such yarn would normally be fed, needle latches having been cleared of the elastic and previously drawn stitches, the latter not being shown for purposes of clearness. Continuing to the right, Fig. 10, needles are drawn down by stitch cam 22, sinkers are pushed in by the point of cam 77 casting off the elastic and old loops, the result being that plain fabric is knitted with elastic inlaid at alternate wales. If at this point two yarns are to be fed in plating relation, or if tuck work is to be done, or if both plating and reverse plating are to be accurately controlled the problem is no greater than it would be in such machines wherein elastic yarn was not involved at all. As previously inlaid by methods heretofore employed, the elastic yarn would maintain needles in misalignment at the left of Fig. 10 even to the point of knitting at the main feeding station. By getting more elastic material into the fabric at each revolution of the machine, the elastic, although under enough tension for proper control, does allow alignment of needles and proper control of plating, reverse plating, or other work wherein misalignment of the knitting instrumentalities would adversely affect the same.

In Fig. 13 a sinker has been shown having a nib 3 which corresponds to the nib 3 of Figs. 1 through 5. The elastic yarn 10 is shown as drawn over the nib and in a second position 10' to which it would have dropped prior to knitting at the next following non-elastic yarn feeding station. In Fig. 12 this same elastic yarn is shown as it would be drawn over a nib 79 of a reverse plating type sinker 80. Said elastic yarn would thereafter be dropped down from the nib to the inclined surface 81 at 10'. In certain instances it is not so convenient to draw over the tops of nibs of sinkers adapted to reverse plate since these nibs are quite rounded at their top surface. In such event an elastic yarn may be drawn as shown in Fig. 11, over an inclined forward edge 81' and later said sinker moved outwardly releasing tension on the elastic yarn 10 by dropping the same to a lower position 10' along said inclined edge. In this particular instance all sinkers are controlled alike, that is, it is not necessary to push said sinkers inwardly while retaining others outwardly.

In Fig. 18 a diagrammatic illustration of a machine construction and its method of operation appear wherein in addition to the elastic yarn fed, there are two non-elastic yarn feeds. The elastic yarn feeding means 9 feeds the elastic yarn 10 as previously described and thereafter, an auxiliary feed 82 intervenes between that elastic feeding station and a main yarn feeding station at which a guide 83 and other similar means may feed a second non-elastic yarn. In this particular example it is contemplated to plate and float for pattern effects, to knit tuck work, or to produce mock wrap, so-called. To this end jacks 84 having selective butts 85 and master butts 86 are placed beneath each needle. The said jacks have butts 87 and 88, the only distinction between these being that butts 88

are long and butts 87 are short. Selecting members 89 are so controlled as to elevate jacks having long butts 88 whereupon their master butts 86 pass up a cam 90.

- 5 A cam 91 acts as a stitch drawing cam at this auxiliary non-elastic yarn feed and cam 92 serves as a sort of raise cam and also as a jack lowering cam. The elongated cam 93 is a sort of guard cam for both non-elastic yarn feeds, and also serves at certain times as an instep cam. Jack cam 94 is effective on butts 88 to raise certain jacks and needles at the feed 83, it being evident at this point that the top plunger 89 and cam 94 may be used to elevate selected needles at either of the feeding stations 82 or 83. Such manipulation of needles is desired when tucking is to be done such as in the knitting of a tuck top or edge of any type, especially the type of co-pending application Serial #332,161. Of course, tucking may be for ornamental purposes throughout any parts of a knitted article. Cams 95, 96 and 97 function as described in the application just mentioned for purpose of drawing stitches of yarn fed by yarn feeding means 83. At the elastic yarn feeds, cam 25' functions with raise cam 20' in drawing elastic yarn, selection of needles being controlled by movable cam 98 which acts upon jack butts 88.
- 10 30 Three pathways of butts are shown, a lower pathway 99 indicating the path of jack butts 87 and 88. At the first knitting station all jacks are raised and all needle butts move in pathway 100, top plunger 89 selecting jacks while master butts 86 of jacks thus selected raise up cam 90. All needles will knit the yarn fed at 82 since needle butts pass downwardly beneath cam 91. Cam 92 then serves to raise needles to a yarn taking position but not a latch clearing position.
- 15 35 Cam 94 contacts long butts 88 only so that jacks having such butts control their needles to be raised to clearing position as indicated by the pathway of needle butts adjacent to cam 95. All needles either draw yarn or knit beneath cam 96 and thereafter alternate needles, or such needles as are desired, draw elastic yarn 10 beneath cam 25', the cam 98 acting as a selecting means to elevate alternate needles to elastic yarn taking position. What has just been described with respect to Fig. 18 applies to knitting in the top or selvage portion of a knitted fabric and wherein tuck work is done as in application Serial #332,161. When tuck work is no longer to be continued, a front stitch cam 55 (not shown) is moved into position at the main yarn feeding station, that serving to clear all needle latches so that all needles will take yarn and knit at the feed 83.
- 20 40 The employment of three feeds allows the elastic to be spaced yet avoids floating the same across the needle circle. This type of machine is obviously to be desired when wrap patterns are to be knitted and when elastic yarn is to be knitted in non-adjacent courses.
- 25 45 50 55 60 65 70 75 The invention has been described by reference to certain specific embodiments of the same in a typical hosiery machine of circular independent needle type, but it is to be understood that the principles are applicable to other types of machines such as flat bed machines, either of independent or united needle type. Variations as to spacing of needles for taking elastic yarn and wales at which the same may be inlaid are contemplated as also are the number of courses

over which said yarn may be spaced. The invention is defined in the appended claims.

I claim:

1. A method of incorporating a non-elastic and elastic yarn in a plain knitted fabric by drawing the non-elastic yarn over sinker edges and drawing said elastic yarn over the nibs of sinkers positioned above the aforesaid sinker edges.

2. A method of incorporating non-elastic and elastic yarn in plain knitted fabrics by drawing the non-elastic yarn over sinker edges and drawing the said elastic yarn over the nibs of the said sinkers which are positioned above the said sinker edges and thereafter dropping said yarn from the nibs prior to inlaying in association with a non-elastic yarn.

3. A method of inlaying an elastic yarn in circular independent needle knitting machines including the steps of projecting sinkers inwardly as the elastic yarn is fed to the hooks of needles, drawing said yarn over sinker nibs positioned above the usual yarn drawing edges and thereafter raising needles until the elastic passes beneath the latches thereof prior to taking the non-elastic yarn with which the elastic is to be inlaid.

4. A method of inlaying an elastic yarn in circular independent needle knitting machines including the steps of positioning sinkers inwardly to such a point that as the elastic yarn is fed to the hooks of needles, said yarn will be drawn over relatively raised surfaces on said sinkers, and thereafter moving said sinkers to a position in which said elastic yarn will drop from said relatively raised surfaces to lower surfaces prior to clearing needle latches and knitting a non-elastic yarn.

5. In a knitting machine the combination of latch needles, sinkers with nibs, means for feeding non-elastic yarns, means for feeding an elastic yarn in advance of the means for feeding said non-elastic yarns, and means for so controlling needles that the elastic yarn will be taken in needle hooks initially but will be cleared below needle latches prior to feeding non-elastic yarns, and means for so controlling sinkers that nibs thereof will be in position to have the elastic yarn drawn over them at said elastic yarn feeding station.

6. In a knitting machine the combination of independently actuated latch needles and sinkers having nibs, two yarn feeding stations, one at which non-elastic yarns are fed and a second at which an elastic yarn is fed, said elastic yarn feeding station being in advance of said non-elastic yarn feeding station, means for so controlling sinkers that some at least of them will be in a forward position so that elastic yarn will be drawn over relatively raised surfaces thereon at said elastic yarn feeding station, and other means for withdrawing sinkers so that said elastic yarn may drop from said relatively raised surfaces prior to knitting at the said non-elastic yarn feeding station.

7. In a knitting machine the combination of needles and independently actuated sinkers, beds for needles and sinkers, some at least of said sinkers having yarn drawing edges and relatively elevated nibs with suitable surfaces above them over which yarn may be drawn, differentiating butts on said sinkers and a cam for moving sinkers outwardly relatively to needle and sinker beds, said cam being so constructed as to operate 75

on some of said sinker butts but to fall to contact others of said sinker butts.

8. A method of knitting including depressing needles to a yarn drawing position to draw relatively non-elastic yarn over the edges of companion sinkers, causing sinkers to be advanced and causing alternate needles to be elevated to a position to engage elastic yarn in their hooks but insufficiently to clear their latches of the non-elastic yarn, thereafter causing the said alternate needles to be depressed to draw the elastic yarn over edges of the sinkers above the mentioned edges, and thereafter elevating the needles to clear the latches of the elastic and non-elastic yarns, and then again knitting non-elastic yarn.

9. A circular knitting machine having independently movable needles and sinkers, means for feeding non-elastic and elastic yarns to the needles, the said elastic yarn being fed to alternate needles only and at a point spaced from the feeding of non-elastic yarn, alternate sinkers having edges over which the needles draw the non-elastic yarn, each said sinker having a throat at one end of the said edge and having a nib above the throat, said nib having a horizontal yarn drawing edge, means for causing the alternate needles to engage the elastic yarn and draw the same over the horizontal edges of the sinker nibs of alternate sinkers, approximately to the first mentioned horizontal edges of the sinkers.

10. A circular knitting machine having independently movable needles and sinkers, means for feeding non-elastic yarn to all the needles for a plurality of courses and for feeding elastic yarn to alternate needles only and during the knitting of the same courses, means for causing alternate needles to knit the non-elastic yarn continuously during the knitting of the said courses and means for causing the intermediate needles to tuck non-elastic yarn during the knitting of some only of the same courses, and for thereafter causing the said intermediate needles to knit the non-elastic yarn continuously, the said elastic yarn being fed to said alternate needles at a point spaced from the feeding of non-elastic yarn, alternate sinkers having edges over which the needles draw the non-elastic yarn, each said sinker having a throat at one end of the said edge and having a nib above the throat, said nib having a horizontal yarn drawing edge, and means for causing the alternate needles only to engage the elastic yarn and draw the same over the horizontal edges of the sinker nibs of alternate sinkers, approximately to the first mentioned horizontal edges of the sinkers.

11. A circular knitting machine having independently movable needles and sinkers, means for feeding two non-elastic yarns to all the needles for a plurality of courses and for feeding elastic yarn to alternate needles only and during the knitting of the same courses, means for causing alternate needles to knit one said non-elastic yarn continuously during the knitting of the said courses and means for causing the intermediate needles to tuck said last mentioned non-elastic yarn during the knitting of some only of the said courses, and for thereafter causing the said intermediate needles to knit the non-elastic yarn continuously, the said elastic yarn being fed to said alternate needles at a point spaced from the feeding of non-elastic yarn, alternate sinkers having edges over which the needles draw the non-elastic yarn, each said

sinker having a throat at one end of the said edge and having a nib above the throat, said nib having a horizontal yarn drawing edge, and means for causing the alternate needles only to engage the elastic yarn and draw the same over the horizontal edges of the sinker nibs of alternate sinkers, approximately to the first mentioned horizontal edges of the sinkers.

12. A circular knitting machine having independently movable needles and sinkers, means for independently feeding two non-elastic yarns to all the needles for a plurality of courses and for feeding elastic yarn to every other needle only and during the knitting of the said plurality of courses, means for causing the said every other needle to knit one said non-elastic yarn continuously during the knitting of the said plurality of courses and means for causing the intermediate needles to tuck said last mentioned non-elastic yarn during the knitting of some only of the said plurality of courses, and for thereafter causing the said intermediate needles to knit the non-elastic yarn continuously, the said elastic yarn being fed to said every other needle at a point spaced from the feeding of non-elastic yarn, every other sinker having edges over which the needles draw the non-elastic yarn, each said sinker having a throat at one end of the said edge and having a nib above the throat, said nib having a horizontal yarn drawing edge, means for causing the said every other needle only to engage the elastic yarn and draw the same over the horizontal edges of the sinker nibs of every other sinker, approximately to the first mentioned horizontal edges of the sinkers, and means for thereafter withdrawing the said every other sinker thereby causing the elastic yarn to drop off the mentioned sinker nibs and on to the mentioned sinker edges.

13. A circular knitting machine having independently movable needles and sinkers, means for independently feeding two non-elastic yarns to all the needles for a plurality of courses and for feeding elastic yarn to every other needle only and during the knitting of the said plurality of courses, means for causing the said every other needle to knit one said non-elastic yarn continuously during the knitting of the said plurality of courses and means for causing the intermediate needles to tuck said last mentioned non-elastic yarn during the knitting of some only of the said plurality of courses, and for thereafter causing the said intermediate needles to knit the non-elastic yarn continuously, the said elastic yarn being fed to said every other needle at a point spaced from the feeding of non-elastic yarn, every other sinker having edges over which the needles draw the non-elastic yarn, each said sinker having a throat at one end of the said edge and having a nib above the throat, said nib having a horizontal yarn drawing edge, and means for causing the said every other needle only to engage the elastic yarn and draw the same over the horizontal edges of the sinker nibs of every other sinker, approximately to the first mentioned horizontal edges of the sinkers.

14. A circular knitting machine having independently movable needles and sinkers, means for independently feeding two non-elastic yarns to all the needles for a plurality of courses and for feeding elastic yarn to alternate needles only and during the knitting of the said plurality of courses, means for causing alternate needles to knit one said non-elastic yarn continuously dur-

ing the knitting of the said plurality of courses and means for causing the intermediate needles to tuck said last mentioned non-elastic yarn during the knitting of some only of the said plurality of courses, and for thereafter causing the said intermediate needles to knit the non-elastic yarn continuously, the said elastic yarn being fed to said alternate needles at a point spaced from the feeding of non-elastic yarn, alternate sinkers having edges over which the needles draw the non-elastic yarn, each said sinker having a throat at one end of the said edge and having a nib above the throat, said nib having a horizontal yarn drawing edge, means for causing the alternate needles only to engage the elastic yarn and draw the same over the horizontal edges of the sinker nibs of alternate sinkers, approximately to the first mentioned horizontal edges of the sinkers, and means for thereafter withdrawing the said alternate sinkers thereby causing the elastic yarn to drop off the mentioned sinker nibs and on to the mentioned sinker edges.

15. A circular knitting machine having independently movable needles and sinkers, means for independently feeding two non-elastic yarns to all the needles for a plurality of courses and for feeding elastic yarn to alternate needles only and during the knitting of the said plurality of courses, means for causing alternate needles to knit one said non-elastic yarn continuously during the knitting of the said plurality of courses, means for causing alternate needles to knit one said non-elastic yarn continuously during the knitting of the said plurality of courses and means for causing the intermediate needles to tuck said last mentioned non-elastic yarn during the knitting of some only of the said plurality of courses, and for thereafter causing the said intermediate needles to knit the non-elastic yarn continuously, the said elastic yarn being fed to said alternate needles at a point spaced from the feeding of non-elastic yarn, alternate sinkers having edges over which the needles draw the non-elastic yarn, each said sinker having a throat at one end of the said edge and having a nib above the throat, said nib having a horizontal yarn drawing edge, and means for causing the alternate needles only to engage the elastic yarn and draw the same over the horizontal edges of the sinker nibs of alternate sinkers, approximately to the first mentioned horizontal edges of the sinkers.

16. A circular knitting machine having independently movable needles and sinkers, means for independently feeding non-elastic yarn to all the needles for a plurality of courses and for feeding elastic yarn to every other needle only and during the knitting of the said plurality of courses, means for causing the said every other needle to knit said non-elastic yarn continuously during the knitting of the said plurality of courses and means for causing the intermediate needles to tuck said non-elastic yarn during the knitting of some only of the said plurality of courses, and for thereafter causing the said intermediate needles to knit the non-elastic yarn continuously, the said elastic yarn being fed to said every other needle at a point spaced from the feeding of non-elastic yarn, every other sinker having edges over which the needles draw the non-elastic yarn, each said sinker having a throat at one end of the said edge and having a nib above the throat, said nib having a horizontal yarn drawing edge, means for causing the said every other needle only to engage the elastic

yarn and draw the same over the horizontal edges of the sinker nibs of every other sinker, approximately to the first mentioned horizontal edges of the sinkers, and means for thereafter withdrawing the said every other sinker thereby causing the elastic yarn to drop off the mentioned sinker nibs and on to the mentioned sinker edges.

17. A circular knitting machine having independently movable needles and sinkers, means for independently feeding non-elastic yarn to all the needles for a plurality of courses and for feeding elastic yarn to every other needle only and during the knitting of the said plurality of courses, means for causing the said every other needle to knit said non-elastic yarn continuously during the knitting of the said plurality of courses and means for causing the intermediate needles to tuck said non-elastic yarn during the knitting of some only of the said plurality of courses, and for thereafter causing the said intermediate needles to knit the non-elastic yarn continuously, the said elastic yarn being fed to said every other needle at a point spaced from the feeding of non-elastic yarn, every other sinker having edges over which the needles draw the non-elastic yarn, each said sinker having a throat at one end of the said edge and having a nib above the throat, said nib having a horizontal yarn drawing edge, and means for causing the said every other needle only to engage the elastic yarn and draw the same over the horizontal edges of the sinker nibs of every other sinker, approximately to the first mentioned horizontal edges of the sinkers.

18. A circular knitting machine having independently movable needles and sinkers, means for independently feeding non-elastic yarn to all the needles for a plurality of courses and for feeding elastic yarn to alternate needles only and during the knitting of the said plurality of courses, means for causing alternate needles to knit said non-elastic yarn continuously during the knitting of the said plurality of courses and means for causing the intermediate needles to tuck said non-elastic yarn during the knitting of some only of the said plurality of courses, and for thereafter causing the said intermediate needles to knit the non-elastic yarn continuously, the said elastic yarn being fed to said alternate needles at a point spaced from the feeding of non-elastic yarn, alternate sinkers having edges over which the needles draw the non-elastic yarn, each said sinker having a throat at one end of the said edge and having a nib above the throat, said nib having a horizontal yarn drawing edge, means for causing the alternate needles only to engage the elastic yarn and draw the same over the horizontal edges of the sinker nibs of alternate sinkers, approximately to the first mentioned horizontal edges of the sinkers, and means for thereafter withdrawing the said alternate sinkers thereby causing the elastic yarn to drop off the mentioned sinker nibs and on to the mentioned sinker edges.

19. A circular knitting machine having independently movable needles and sinkers, means for independently feeding non-elastic yarn to all the needles for a plurality of courses and for feeding elastic yarn to alternate needles only and during the knitting of the said plurality of courses, means for causing alternate needles to knit said non-elastic yarn continuously during the knitting of the said plurality of courses, means for causing alternate needles to knit one said non-elastic

yarn continuously during the knitting of the said plurality of courses and means for causing the intermediate needles to tuck said non-elastic yarn during the knitting of some only of the said plurality of courses and for thereafter causing the

5 rality of courses, and for thereafter causing the said intermediate needles to knit the non-elastic yarn continuously, the said elastic yarn being fed to said alternate needles at a point spaced from the feeding of non-elastic yarn, alternate sinkers
10 having edges over which the needles draw the non-elastic yarn, each said sinker having a throat at one end of the said edge and having a nib above the throat, said nib having a horizontal yarn drawing edge, and means for causing the
15 alternate needles only to engage the elastic yarn and draw the same over the horizontal edges of the sinker nibs of alternate sinkers, approximately to the first mentioned horizontal edges of the sinkers.

20. A circular knitting machine having independently movable needles and sinkers, means for independently feeding a non-elastic yarn and an elastic yarn to the needles of a knitting machine, means for causing all the needles to knit the non-

25 means for causing all the needles to knit the non-elastic yarn and means for causing the hooks of alternate needles only to engage the elastic yarn in their hooks, the said elastic yarn being fed to the hooks of the said alternate needles at a point spaced from the feeding of the non-elastic

30 yarn, alternate sinkers having edges over which the needles draw the non-elastic yarn, each said sinker having a throat at one end of the said edge and having a nib above the throat, said nib having a horizontal yarn drawing edge, means caus-

35 ing the said alternate needles only to engage the elastic yarn and draw the same over the horizontal edges of the sinker nibs of alternate sinkers, approximately to the first mentioned horizontal edges of the sinkers, and means for thereafter
40 withdrawing the said alternate sinkers thereby causing the elastic yarn to drop off the mentioned sinker nibs and on to the mentioned sinker edges.

45 21. A circular knitting machine having independently movable needles and sinkers, means for independently feeding a non-elastic yarn and an elastic yarn to the needles of a knitting machine, means for causing all the needles to knit the non-elastic yarn and means for causing the

50 hooks of every other needle only to engage the elastic yarn, the said elastic yarn being fed to the hooks of the said every other needle at a point spaced from the feeding of the non-elastic yarn, the sinkers having edges over which the needles draw the non-elastic yarn, each said sinker having a throat at one end of the said edge and having a nib above the throat, said nib having a horizontal yarn drawing edge, means causing the

60 *Method of joining drawing edge, means causing the said every other needle only to engage the elastic yarn and draw the same over the horizontal edges of the sinker nibs of every other sinker, approximately to the first mentioned horizontal edges of the sinkers, and means for thereafter withdrawing the said every other sinker thereby causing the elastic yarn to drop off the mentioned sinker nibs and on to the mentioned sinker edges.*

22. A circular knitting machine having independently movable needles and sinkers, means for independently feeding a non-elastic yarn and an elastic yarn to the needles, means causing all the needles to knit the non-elastic yarn and means causing the hooks of alternate needles only to engage the elastic yarn, the said elastic yarn being fed to the hooks of the said alternate needles at a point spaced from the feeding of the non-elas-

tic yarn, the sinkers having edges over which the needles draw the non-elastic yarn, each said sinker having a throat at one end of the said edge and having a nib above the throat, said nib having a horizontal yarn drawing edge, and means causing the said alternate needles only to engage the elastic yarn and draw the same over the horizontal edges of the sinker nibs of alternate sinkers, approximately to the first mentioned horizontal edges of the sinkers.

23. A circular knitting machine having independently movable needles and sinkers, means for independently feeding a non-elastic yarn and an elastic yarn to the needles, means causing all the needles to knit the non-elastic yarn and means causing the hooks of every other needle only to engage the elastic yarn in their hooks, the said elastic yarn being fed to the hooks of the said every other needle at a point spaced from the feeding of the non-elastic yarn, every other sinker having edges over which the needles draw the non-elastic yarn, each said sinker having a throat at one end of the said edge and having a nib above the throat, said nib having a horizontal yarn drawing edge, and means causing the said every other needle only to engage the elastic yarn and draw the same over the horizontal edges of the sinker nibs of every other needle, approximately to the first mentioned horizontal edges of the sinkers.

24. A circular knitting machine having independently movable needles and sinkers, means for independently feeding a non-elastic yarn and an elastic yarn to the needles of a knitting machine, means for causing all the needles to knit the non-elastic yarn and means for causing the hooks of alternate needles only to engage the elastic yarn in their hooks, the said elastic yarn being fed to the hooks of the said alternate needles at a point spaced from the feeding of the non-elastic yarn, alternate sinkers having edges over which the needles draw the non-elastic yarn, there being edges elevated above the said sinker edges, and means causing said every other needle only to engage the elastic yarn and draw the same over the said elevated edges, approximately to the first mentioned horizontal edges of the sinkers, and means for thereafter withdrawing the said alternate sinkers thereby causing the elastic yarn to drop off the mentioned sinker nibs and on to the mentioned sinker edges.

25. A circular knitting machine having independently movable needles and sinkers, means for independently feeding a non-elastic yarn and an elastic yarn to the needles of said knitting machine, means for causing all the needles to knit the non-elastic yarn and means for causing the hooks of every other needle only to engage the elastic yarn, the said elastic yarn being fed to the hooks of the said every other needle at a point spaced from the feeding of the non-elastic yarn, the sinkers having edges over which the needles draw the non-elastic yarn, there being edges elevated above the said sinker edges, and means causing said every other needle only to engage the elastic yarn and draw the same over the said elevated edges, approximately to the first mentioned horizontal edges of the sinkers, and means for thereafter withdrawing the said every other sinker thereby causing the elastic yarn to drop off the mentioned elevated edges and onto the mentioned sinker edges.

26. A circular knitting machine having inde-

pendently movable needles and sinkers, means for independently feeding a non-elastic yarn and an elastic yarn to the needles, means causing all the needles to knit the non-elastic yarn and means causing the hooks of alternate needles only to engage the elastic yarn, the said elastic yarn being fed to the hooks of the said alternate needles at a point spaced from the feeding of the non-elastic yarn, the sinkers having edges over which the needles draw the non-elastic yarn, and edges elevated above the said sinker edges, and means causing the said alternate needles only to engage the elastic yarn and draw the same over the said elevated edges approximately to the level of the first mentioned edges of the sinkers.

27. A circular knitting machine having independently movable needles and sinkers, means for independently feeding a non-elastic yarn and an elastic yarn to the needles, means causing all the needles to knit the non-elastic yarn and means causing the hooks of every other needle only to engage the elastic yarn in their hooks, the said elastic yarn being fed to the hooks of the said every other needle at a point spaced from the feeding of the non-elastic yarn, every other sinker having edges over which the needles draw the non-elastic yarn, there being edges elevated above the said sinker edges, and means causing the said alternate needles only to engage the elastic yarn and draw the same over the said elevated edges approximately to the first mentioned horizontal edges of the sinkers.

28. A method of knitting including knitting a non-elastic yarn into plain knitted fabric and feeding an elastic yarn to recurrent needles only and measuring that yarn by drawing the same over nibs of recurrent sinkers and then causing the said elastic yarn to be dropped from the said sinker nibs prior to again knitting non-elastic yarn.

29. A method of knitting including drawing a non-elastic yarn into knitted stitches to knit a plain fabric section and feeding an elastic yarn to recurrent, spaced needles only and measuring that elastic yarn by drawing it over nibs of sinkers, and thereafter, withdrawing said sinkers over the nibs of which said elastic yarn is drawn so as to drop the elastic yarn from those nibs whereupon needles intermediate said recurrent, spaced needles may be raised to interlace the elastic yarn in front and in back of predetermined needles without disturbing the alignment of said needles.

30. A method of knitting including knitting a relatively non-elastic yarn by all of the needles of a series of needles, then feeding a relatively elastic thread to the needles in such a manner that it is positioned in the hooks of alternate needles but is not engaged by intermediate needles, the said non-elastic yarn previously drawn still remaining in the hooks of the needles, then causing alternate needles to draw the elastic thread over sinker nibs while intermediate needles remain at a low level so as not to engage the said elastic thread, thereafter withdrawing sinkers so as to drop the elastic thread from the nibs thereof and then raising intermediate needles in front of said elastic thread thereby to interlace said elastic thread in front of and in back of needles without disturbing the alignment thereof.
